UNITED STATES PATENT OFFICE.

JOHN J. SULLIVAN, OF IPSWICH, MASSACHUSETTS.

MACHINE FOR SEWING ON BUTTONS.

SPECIFICATION forming part of Letters Patent No. 595,743, dated December 21, 1897.

Application filed May 14, 1896. Serial No. 591,542. (No model.)

To all whom it may concern:

Be it known that I, JOHN J. SULLIVAN, a citizen of the United States, residing at Ipswich, in the county of Essex and State of Massachusetts, have invented certain new and useful Improvements in Button-Sewing Machines, of which the following is a specification, reference being had therein to the accompanying drawings.

10 My invention relates to that class of button-sewing machines for attaching buttons to shoes or other articles, and has for its object to provide a machine of the class referred to with means by which when a button has been 15 secured by a proper number of stitches or when the last of a series of buttons has been sewed on the needle-thread will be automatically severed, so that there will be no thread extending from one button to another on the 20 upper or fair side of the work.

In the accompanying drawings, Figure 1 is a side elevation of a button-sewing machine embodying my invention. Fig. 2 is a detail view of a portion of the mechanism for operating the thread-cutter and the tension-release. Fig. 3 is a plan view of the machine shown in Fig. 1. Figs. 4, 5, 6, and 7 are detail views to illustrate the thread-cutting device. Fig. 8 is a detail view of the button-feeder. Fig. 9 is a detail plan and end view of the slide which carries the movable blade or cutter.

A denotes the standard of the machine-frame, from which standard extends forward 35 horizontally the integral overhanging arm A' and the work-supporting arm or cylinder A², these parts constituting the frame of the machine.

The stitch-forming mechanism of the machine herein shown is that of the well-known "Singer" oscillating-shuttle lock-stitch machine. In the particular form of oscillating-shuttle machine herein shown the needle-bar f is reciprocated vertically in a horizontally-45 swinging frame F, pivoted at f' and connected by a rod or link f³ with the free end of a horizontal lever f⁴, pivoted at f⁵ and provided between its ends with a pin or roller-stud entering a cam-groove e² in a cam-cylinder E, 50 mounted to rotate freely on the driving-shaft B and intermittently rotated by a cam-actuated lever-dog e, engaging teeth on said cam-

cylinder and operating as fully described in United States Patent No. 541,840, dated July 2, 1895. By reason of the above-described 55 connections of the needle-bar with the cam e² horizontal movements will be imparted to said needle-bar and to the needle carried thereby to form overseaming-stitches in a well-known manner. 60

G is a button-hopper from which the buttons pass down through the chute H to the needle. The driving-shaft B is provided with a worm b³, meshing with a worm-wheel g on the lower end of a vertical shaft g', extending up within the hopper G and carrying a series of brushes g², which serve to work the buttons outward from said hopper into said chute, so that they can be carried from the lower end of the latter to the needle by 70 the horizontally-swinging button-feeder or arm m, attached to the lower end of a vertical rock-shaft M. The shaft M has at its upper end an arm m', connected by a rod m² to the lower or free end of a lever m³, pivoted at m⁴ and having between its ends a pin or roller-stud m⁵, entering the cam-groove e³ of the cam-cylinder E. 75

The driving-shaft B is provided at its rear end with the loose pulley b⁴ and the fast pulley b⁵. 80

N is a starting and stopping lever having a belt-shifter n for transferring the driving-belt from the fast pulley to the loose pulley, and vice versa, and having also an arm n' to be 85 engaged by a hook on the rear end of a retaining-latch n², the outer end of said lever N being pressed outward or toward said pulleys by the spring n³. Rigid with the lever N is an arm N' to be connected by a rod n⁴ 90 with a treadle to enable the operator to transfer a belt from the loose pulley to the fast pulley to set the machine in operation.

The inner or forward end of the latch n² extends within the range of a pin c⁵ on the cam-cylinder E, so that when said cylinder has completed a revolution and a predetermined 95 number of button-attaching stitches have been made said pin will trip said latch and release its rear end from engagement with the arm n' of the lever N to permit the spring n³ to move the lever N into such position as will shift the belt from the fast pulley b⁵ to the loose pulley b⁴ to stop the machine. 100

The presser-foot may be raised to release the work by the ordinary lifter o or by a lever O to be connected with a knee-lever or a treadle.

The features of my improved machine are 5 essentially the same as in the machine embraced by my application filed January 14, 1896, Serial No. 575,445; but instead of making the button-attaching stitches as a part of a continuous seam, as is done by the machine 10 embraced by the said application, and also by the machine embraced by my prior application, Serial No. 541,860, filed March 15, 1895, I have in my improved machine omitted the work-feeding mechanism employed in the 15 machines shown by said applications and have provided an automatic thread-cutting mechanism which will now be described and by means of which, just before the machine is automatically stopped, the needle-thread 20 is severed beneath the work, so that there will be no thread extending from one button to another on the upper or fair side of the work.

D is a rocking thread-cutter shaft having 25 at its rear end an arm d^8 , to which is jointed the lower end of a rod d , connected at its upper end to an arm d' of a short shaft d^2 , having a second arm d^8 provided with a pin or roller stud entering a cam-groove e^4 in the rear face 30 of the cylinder E . The shaft D is provided at its forward end with a rigidly-attached arm or disk d^5 , carrying a block d^6 , having a lug d^7 entering a notch in a slide c , horizontally movable in a suitable guideway formed at the 35 top of the shuttle-race ring C and which slide carries a blade or knife c' , coöperating with a stationary knife or cutter c^2 , fixed to said shuttle-race ring. Thus when in the operation of the machine a desired number of button-attaching stitches have been made the 40 shaft D will be rocked slightly from the cam-groove e^4 to move the blade c' toward and slightly past the cutting edge of the stationary cutter c^2 to sever the needle-thread 45 beneath the work.

To prevent the end of the severed needle-thread from being pulled upward through the eye of the needle by the take-up, I provide a thread-nipper which engages with the end of 50 the thread between the cutting device and the needle, said thread-nipper in the form of my invention herein shown consisting of the block c^3 , pressed against by the spring c^4 to cause said block to move forward with the 55 knife c' . The forward end of the block c^3 normally projects beyond the cutting edge of the knife c' , so that said end of said block will come in contact with the lower part of the cutter c^2 (to nip the part of the loop of needle-thread extending downward between these 60 parts at the time the cutting device is to be operated) before the knife c' passes by the edge of the cutter c^2 to sever the thread, said block being yieldingly held in contact with the 65 lower part of the cutter c^2 during the thread-nipping operation by the spring c^4 . When the cutter or knife c' is retracted by the return

or backward rocking movement of the disk d^5 , moving with the shaft D , the block O engages the slight lip on the rear end of the block c^3 , and thus causes said last-named block to be moved away from the cutter c^2 to release the thread. Although it might appear from the drawings that the thread was severed between the nipping device and the needle, (owing to the location of the said nipping device below the cutters,) such, however, is not the case, as one limb only of the downwardly-extending needle-loop is severed, the thread running from the nipping device downward 80 and thence again upward at one side of the cutters to the needle, so that the nipping device really holds the needle-thread between the cutting device and the needle, as stated.

To prevent the take-up from pulling the 85 thread out of the thread-nipping device owing to too strong a frictional hold on the thread by the tension device J , the machine is preferably provided with a tension-releasing device consisting of a finger k at the forward end 90 of a rock-shaft K , said shaft having at its rear end an arm k' , held by a spring k^2 against the arm d^8 of the shaft d^2 , from which the cutter-operating shaft D is actuated, so that at the moment when the thread is to be severed the 95 said shaft K will be rocked slightly to cause the finger k to enter between the disks of the tension device J , and thus by forcing said disks apart to release their grasp on the thread. In order, however, that the thread when thus released will still be under proper control, there is an auxiliary or light tension device J' , which will still hold the thread lightly when it is released from the grasp of the disks of the main tension device J . This automatic tension-releasing and thread-controlling device is, however, not herein claimed, as it is not of my invention.

In the operation of my improved machine herein shown the parts are so timed that when 110 a desired number of button-attaching stitches have been made and just before the machine is to be automatically stopped, or, in other words, just as the last one of a series of button-attaching stitches is being completed, the 115 thread-cutting device is operated to sever the thread, and the machine will then be stopped by the automatic stop-motion mechanism hereinbefore described, with the end of the 120 severed needle-thread held by the thread-nipping device. When the machine is again started by the operator, the thread-nipping device will still hold the thread until a first fastening stitch has been made, and the button-feeder m is then operated to carry a button from the lower end of the button-chute H and present the same to the needle, and also, in coöperation with the presser-foot, hold the button in sewing position until one or more button-attaching stitches have been 130 made, and the button-sewing and thread-severing operations are then repeated for the next button. As no automatic work-feeding device is employed in the machine herein

shown, it will be understood that the work will be fed or moved forward after each button-attaching operation by the attendant.

As I believe that I am the first to apply an automatic thread-cutting device to a button-sewing machine provided with an automatic button-feeding mechanism to sever the thread when desired, I do not wish to be understood as limiting my invention to the details herein shown or to any particular kind of stitch-forming mechanism, as the general features of the button-sewing machine may be varied widely without departing from the spirit of my invention.

Having thus described my invention, I claim and desire to secure by Letters Patent—

1. In a button-sewing machine, the combination with a stitch-forming mechanism comprising a needle and a loop-taking device coöperating therewith in the formation of stitches, of an automatic button-feeding mechanism for successively presenting buttons to said stitch-forming mechanism and for holding the same in place while being sewed to the work, and an automatic thread-cutting device for severing the needle-thread after each button has been attached.

2. In a button-sewing machine, the combination with stitch-forming and button feeding and holding mechanisms, of an automatic stop-motion device, and an automatic thread-cutting device for severing the needle-thread

after each button has been attached and just before the machine is stopped by the said stop-motion device.

3. In a button-sewing machine, the combination with a stitch-forming mechanism comprising a needle and a loop-taking device coöperating therewith in the formation of 40 stitches, of a button-feeding mechanism serving to successively present buttons to said stitch-forming mechanism and to hold them in place while being attached to the work, an automatic thread-cutting device, for severing the needle-thread after each button has been attached, and an automatic thread-nipping device for holding the end of the needle-thread when severed.

4. In a button-sewing machine, the combination with a stitch-forming mechanism comprising a needle and a loop-taking device coöperating therewith in the formation of 55 stitches, of a button-holding device which retains the buttons in place while being attached to the work, an automatic thread-cutting device for severing the needle-thread after each button has been attached, and an automatic thread-nipping device for holding the ends of the needle-thread when severed.

In testimony whereof I affix my signature in presence of two witnesses:

JOHN J. SULLIVAN.
